[57] CLAIM

The ornamental design for a camera case, substantially
as shown and described.

DESCRIPTION

FIG. 1 is a front, top and right side perspective view of
a camera case showing our new design;

FIG. 2 is a rear, top and left side perspective view
thereof;

FIG. 3 is a front elevational view thereof;

FIG. 4 is a right side elevational view thereof, the oppo-
site side being a mirror image;

FIG. 5 is a top plan view thereof;

FIG. 6 is a rear elevational view thereof;

FIG. 7 is a bottom plan view thereof;

FIG. 8 shows a right side elevational view of the cam-
era case with a cover opened; and

FIG. 9 shows a front, top and right side perspective
view of the camera case with the cover opened.
